UNITED STATES PATENT OFFICE.

WILLIAM J. HINES, OF HARTFORD, CONNECTICUT, ASSIGNOR TO THE FULLER BRUSH COMPANY, OF HARTFORD, CONNECTICUT, A CORPORATION OF CONNECTICUT.

VANITY CASE.

Application filed November 22, 1922. Serial No. 602,520.

To all whom it may concern:

Be it known that I, WILLIAM J. HINES, a subject of the King of Great Britain, and a resident of Hartford, in the county of 5 Hartford and State of Connecticut, have invented new and Improved Vanity Cases, of which the following is a specification.

My invention relates to the class of devices for containing toilet articles, and an 10 object of my invention, among others, is to provide a device of this class that shall be neat in appearance and simple in its construction, thereby enabling it to be produced at comparatively little expense.

15 One form of case embodying my invention and in the construction and use of which the objects herein set out, as well as others, may be attained, is illustrated in the accompanying drawings, in which—

20 Figure 1 is a perspective view of my improved vanity case.

Figure 2 is a view in section through the cover.

25 Figure 3 is a view in section through the box.

Figure 4 is a view in section through the box and cover assembled, but in a plane at right angles to the plane of section of Figures 2 and 3.

30 In the accompanying drawings the numeral 5 indicates the box that is preferably stamped to shape, as from celluloid. This is preferably round in shape with the side located substantially at right angles to the 35 plane of the bottom. A mirror 6 is placed upon the bottom of the box and it is held in place as by means of a retaining ring 7 that is also preferably composed of celluloid or other similar resilient material and

40 round in cross section to increase its resiliency and that may be secured in place in any desired manner.

The cover comprises an inner member 8 that is of cup shape with a closed bottom and 45 this is securely fitted in a recess 9 in an outer member 10 of the cover that is also of cup shape with a flange 11 projecting outwardly therefrom.

50 The outer member 10 is formed with a projection 12 that is stamped from the closed bottom of the outer member and that extends substantially across it from side to side forming a pocket 13 for the reception of a comb or other article, and this pocket 55 has a depression 14 forming a boss for hold-

ing the comb in place. In stamping out this pocket a depression 15 is formed in the bottom of the outer member, a hole extending from said depression to the outer surface of said outer member, and the depression is finally closed by the bottom portion of the inner member 8, as shown in Figure 2 of the drawings.

When the cover is applied to the box the flange 16 formed by the projecting edge 65 of the inner member of the cover closely fits within the box and with its edge preferably against the ring 7, and the flange 11 rests upon the edge of the box and projects slightly therebeyond as an element for enabling the cover to be readily removed.

As an aid in removing the cake of powder, which the recess in the cover is formed to receive, a hole 17 is made opening through the cover from the pocket 13, as shown in 75 Figures 1 and 4 of the drawing. An instrument may be inserted through this hole back of the cake of powder and thereby the latter may be readily removed.

It will be understood that the reflecting 80 element located in the bottom of the box may be of any suitable sort of looking glass or mirror, the structure not being limited to any special character of such device.

In accordance with the provisions of the 85 patent statutes I have described the principles of operation of my invention, together with the device which I now consider to represent the best embodiment thereof; but I desire to have it understood that the device shown is only illustrative and that the 90 invention may be carried out by other means.

I claim—

1. A vanity box cover comprising an 95 outer supporting member having a recess with a pocket opening out of the bottom of said recess, and a cup shaped member inserted in said recess with its open end outward and formed to fit and close the 100 opening into a box.

2. A vanity box cover comprising an outer supporting member with a recess therein with a pocket opening out of the bottom of said recess, and a radially projecting flange at the mouth of said recess, and a cup shaped member inserted in said recess with its open end outward and with its edge projecting beyond said flange to fit and close the opening into a box.

3. A box cover comprising an outer recessed member having the bottom wall of said recess stamped outwardly to form a pocket thereby producing a hole, and a cup shaped member inserted in said recess with its open end outward and its closed end covering said hole said cover being formed to fit and close the opening into a box.
4. A box cover comprising an outer recessed member having the bottom of its recess stamped outwardly to form a pocket open at one end on the outer surface of the cover, said stamped formation producing a hole in the cover, and a cup shaped member inserted in said recess with its open end outward, and its closed end covering said hole said cover being formed to fit and close the opening into a box.
5. A box having a glass resting against the inner surface of the bottom thereof, a ring closely fitting the side of the box and secured against said glass to hold it in position, and a cover comprising an outer recessed member having a flange to fit upon

the edge of the box and an inner cup shaped member with an edge projecting to fit within the box and in proximity to said ring.

6. A vanity box cover comprising an outer supporting member having a pocket formed therein, and a cup shaped member inserted in said recess with its open end outward, said cup shaped member having a hole extending from said pocket into the cup shaped interior of said cup shaped member for the extraction of a cake therefrom said cover being formed to fit and close the opening into a box.

7. A vanity box comprising an outer supporting member having a recess with a pocket opening out of the bottom of said recess and a hole through an edge wall of said pocket to the outer surface of the cover, and a cup-shaped member inserted in said recess with its open end outward and formed to fit within the cover and close one side of said pocket.

WILLIAM J. HINES.
